DESIGN FOR A BABY CARRIAGE

Samuel Drexler, Brooklyn, N. Y., assignor to Meyer S. Harrison and Elias Specter, doing business under the firm name and style of Bilt-Rite Baby Carriage Co., Brooklyn, N. Y.

Application August 31, 1934, Serial No. 53,131

Term of patent 7 years

To all whom it may concern:

Be it known that I, SAMUEL DREXLER, a citizen of the United States, residing at No. 525 Miller Avenue, Brooklyn, in the county of Kings and State of New York, have invented a new, original, and ornamental Design for a Baby Carriage, of which the following is a specification, reference being had to the accompanying drawing, forming a part thereof.

The figure is a perspective of a baby carriage, showing my new design.

I claim:

The ornamental design for a baby carriage, as shown.

SAMUEL DREXLER.
